UNITED STATES PATENT OFFICE.

RICHARD JOSEPH O'BRIEN AND PATRICK J. O'BRIEN, OF BAY BULLS, NEWFOUNDLAND.

BUTTONHOLE SHIELD.

Application filed April 5, 1926. Serial No. 99,889.

This invention has relation to laundering accessories, and aims as its principal object to provide a device for preventing the portion of a starched garment adjacent the buttonholes from being subjected to the stiffening action of starch, whereby to maintain said portion flexible to facilitate the engagement and disengagement of a button with the buttonhole.

10 More specifically the invention comprehends a shield for the portion of a starched garment adjacent the buttonholes, which includes a pair of clamping sections and means of connection therebetween extending 15 through the buttonhole for holding the sections against the opposite surfaces of the garment to exclude and prevent the starch-water from contacting with said portions when the garment is immersed therein.

20 The invention furthermore comprehends a device of the character described which is simple in its construction and mode of use, inexpensive to manufacture, and produce, and which is highly efficient in its purpose.

25 With the above recited and other objects in view, reference is had to the following specification and accompanying drawings in which there is exhibited certain examples or embodiments of the invention which are 30 in no way intended as limitations upon the scope of the appended claims as it is to be clearly understood that variations and modifications which properly fall within the scope of said claims may be resorted to when 35 found expedient.

In the drawings—

Figure 1 is a fragmentary sectional view through a garment with the buttonhole shield in applied position, parts thereof 40 being shown in section;

Fig. 2 is an end view of the shield applied;

Fig. 3 is a fragmentary view of the garment illustrating the shielded or unstarched portion thereof adjacent the buttonhole;

45 Fig. 4 is a sectional view of a slightly modified adaptation of the invention.

Referring to the drawings by characters of reference, A designates a garment, B the buttonhole, and C the shield which includes 50 a pair of mating substantially cup-shaped

sections 10 and 11, the former having a head 12 and the latter provided with a central opening 13. The section 10 is further provided with a central threaded stem 14 adapted to extend through the buttonhole 55 and through the opening 13 in the section 11 and further adapted to receive a wing nut 15 employed for the purpose of clamping and binding the concave confronting faces of the shield sections 10 and 11 against the opposite faces of the garment A, whereby when the garment with the shield applied is immersed in starch-water, the portion D indicated in Fig. 3, adjacent the buttonhole 60 B will be protected against contact of the starch-water therewith so that when the garment is ironed said portion will be unstiffened and flexible to facilitate the engagement or disengagement of the button with the buttonhole B.

In the modified adaptation of the invention illustrated in Fig. 4, the shield section 10^a is formed with a tubular internally threaded stem 14^a adapted to extend through the buttonhole and through the bossed opening 65 13^a in the section 11^a to receive the threaded shank 15^a of a wing screw 16, the section 10^a being provided with a head 12^a. In use and mode of attachment the shield illustrated in Fig. 4 is identical with that described for the first form of the invention.

70 What is claimed is:

1. A shield for excluding starch water from that portion of a garment adjacent the buttonhole when immersed in the starch water, comprising a pair of mating sections having concave confronting faces and interengaging means adapted to extend through the buttonhole for clamping said sections together to embed the edges of the concave 75 faces in the material.

2. A shield of the class and for the purpose described, comprising mating sections having hollow confronting faces adapted to overlie the inner and outer portions of a garment surrounding the buttonhole, and fastening means for the sections extending through the buttonhole.

80 RICHARD JOSEPH O'BRIEN.

85 PATRICK J. O'BRIEN.
